EDGE CUTTER ATTACHMENT FOR SEWING MACHINES

Antonio Alfano, Brooklyn, and Nicholas M. Porreca, Woodside, N.Y.

Application March 13, 1946, Serial No. 654,141

21 Claims. (Cl. 164—17.5)

1

This invention relates to edge cutters for sewing machines, and more particularly aims to provide a novel, efficient, simple and practical edge cutter attachment for sewing machines, so constructed and devised that it may readily be attached on any ordinary sewing machine to convert the same to an edge cutter, and as readily removed to restore the machine to its original form.

Edge cutter machines which are complete in themselves are common on the market, but they are useful for no other purpose than edge cutting and thereby represent an excessive investment, which is idle a substantial part of the time, in shops where a large number of sewing machines are used and in addition one or more edge cutter machines. As the present invention represents an attachment which may be applied to or removed from an ordinary sewing machine in a few minutes by an unskilled person, the sewing machine may thus be used as an edge cutter for the time that edge cutting is required and the rest of the time it is used as a sewing machine. Thus the load factor on all of the machines in the shop is at a maximum.

The above broad as well as additional and more detailed objects will become apparent in the following description, wherein characters of reference refer to like-numbered parts in the accompanying drawing. It is to be noted that the drawing is intended solely for the purpose of illustration, and that it is neither intended nor desired to limit the scope of the invention necessarily to any or all of the specific details of construction shown excepting insofar as they may be deemed essential to the invention.

Referring briefly to the drawing,

Fig. 1 is a fragmentary front elevational view of a sewing machine head with one form of the edge cutting attachment mounted thereon, this form of the attachment embodying a linkage whereby when the needle holder bar of the machine is in raised position the cutter of the attachment is likewise in raised position, as shown herein.

Fig. 2 is a side elevational view of the same.

Fig. 3 is a plan view of the above form of the attachment per se, showing the various parts when the moveable cutter is in its lowermost position.

Fig. 4 is a view substantially similar to Fig. 2, but showing the positions of the various parts when the moveable cutter is in its lowermost position.

Fig. 5 is a fragmentary view of the modified

form of the attachment, as seen in side elevation, the linkage of this modified form being such that when the needle holder is in its maximum raised position the moveable cutter of the attachment is in its lowermost position; otherwise the modified form of the attachment is substantially identical to the first-mentioned form.

Fig. 6 is a perspective view of the removable collar having a rigid pin projecting horizontally therefrom for the purpose to be described hereinafter, which is attached to the needle holder of the machine.

Fig. 7 is a cross-sectional view taken on the line 7—7 of Fig. 2, showing the partly cut-away feeder plate whereby the sewing machine is adapted to utilize the attachment without any impairment to its functioning as a sewing machine when the attachment has been removed.

Fig. 8 is a fragmentary perspective view of one type of sewing machine, showing the invention as exemplified by one form of the edge cutter attachment, applied thereto.

Referring in detail to the drawings, the numeral 10 indicates, fragmentarily, the head of a sewing machine, having the usual foot-supporting bar 11 and the vertically reciprocating needle holder or bar 12 depending therefrom. No means or mechanism for operation of the machine as such nor of the needle bar to cause vertical reciprocation thereof, is shown, as such means and mechanism remain unaltered in the adaptation of the machine to receive the instant attachment, and it is of course well known that the needle bar reciprocates at a speed which is under the control of the operator.

In the case of both forms of the attachment, a collar 13 which is preferably split, as at 14, is attached about the needle bar 12 by means of a screw 15 in the usual manner, and at the proper level as will presently become apparent. A rigid pin 16 projects from the collar 13, and the collar is so positioned in its horizontal plane that the pin projects inward under the machine frame in the same direction as the latter. The collar 13 may be left on the needle bar 12 when the attachment is removed so that the machine may be used as a sewing machine, as it does not interfere with the operation of the machine.

The edge cutter attachment illustrated in Figs. 1, 2, and 4 has a vertical plate 17 having a foot 18 secured thereto through the medium of its shank 19. The foot 18 including its shank 19 may be considered as equivalent to one-half of a standard two-toed sewing machine foot, which may be obtained by cutting the standard foot in

half on a vertical plane passed longitudinally midway of the width of the shank through the space between the toes. This single-toed foot, incidentally, may of course be manufactured as a standard integral part of the attachment.

The three-walled socket 20 at the upper end of the shank 19, which is rectangular in cross-section, has the standard slot 21 cut into its outer wall. The standard bar 11 is rectangular in cross-section at its lower end 22 and is provided with a threaded lateral opening 23 therethrough or thereinto. The shank 19 is secured to the bar 11 in the same manner as the standard foot, that is, by passing a screw through the slot 21 into the hole 23 and tightening the screw. In this case it is preferred to use a screw 24 having an enlarged knurled head 25 so that it may be turned without the aid of a screw driver. Thus, the foot 18 is secured against the bar 11 and rigidly held in proper position, and, since the plate 17 is integral with the shank of the foot, the plate 17 is likewise held fixed in the position shown.

A lever 26 is fulcrumed near its lower end on a pin or screw 27 passing through the plate 17, and at its upper end the lever 26 is provided with a longitudinal slot 28 in which the pin 16 of the collar 13 registers. A second simple lever 29 is fulcrumed substantially intermediate its length on a pin or screw 30 passing through the plate 17 in substantially the position shown. A link 31 having its ends pivoted in the extremities of the two levers 26 and 29, provides together with the latter a linkage whereby the reciprocating vertical motion of the needle bar 12 is utilized to move up and down a depending cutter jaw 32 secured rigidly on the end of the lever 29 by a rivet or screw 33 or by any other means.

Secured against the same side of the plate 17 under the lever 29 by means of screws or rivets 34 or in any other manner, in substantially or approximately horizontal position, is the base or root 35 of a fixed cutter jaw 36 whose inclined and beveled cutting edge 37 is shown in Figs. 2 and 4. The beveled cutting edge of the moveable cutter 32 is shown at 38 in Fig. 1. The needle of the holder 12 is shown at 39, and is adapted to pass downward through the cut-out 40 in the foot 18.

It is now apparent that as the needle holder 12 moves up and down, the moveable cutter jaw 32 will move up and down synchronously therewith and the beveled cutting edges of the cutter jaws 32 and 36 will function as a scissors to cut through the material, being fed through the machine at a short distance from the line of sewing, or stitch, whence the material will be simultaneously sewed and have its edge cut off at a constant distance from the stitch. Naturally, two or more layers of fabric will be passed through the machine for the purpose of sewing them together and simultaneously cutting off the edges.

In order to prevent the feed in fabric from passing under the cutter jaw 36, or, rather, the edge of the fabric the body of which is passing under the foot, it has been found advisable to provide a dependent projection 41 on the extremity of the jaw 36. In order to accommodate this projection as well as to provide a clearing for the moveable cutter jaw 32 in its lowermost position, it has been found desirable to alter the feed plate 42 of the machine in the following manner. This plate, which is secured to the fabric feed mechanism, not shown, in the table of the machine under the needle, by means of screws, not shown, passed through holes 43, has, as is well known,

a series, such as three, of parallel spaced walls 44, 45, and 46 the spaces or slots 47 between which constitute openings through the plate 42. In the standard type of feed plate 42, the wall 45 is broken away at the middle for a distance, to provide a clearance 48 for the needle. To adapt the standard feed plate 42 to the mounting of the edge cutter attachment on the machine, a portion of the wall 46 is also broken away, but forward of the midpoint of the wall and of a length sufficient to provide a clearance space 49 in which the projection 41 may register. Experience has taught that the above alteration in the feed plate 42 has no effect whatever upon the normal feeding action of the machine when used as a simple sewing machine, without the edge cutter attachment.

In the modified form of the attachment shown in Fig. 5, parts which are similar or equivalent to parts of the first-described form, are indicated by the same reference numerals followed by the subscript *a*. The only substantial difference between the two forms is that the lever 26a is pivoted to the plate 17a at its extremity at 27a, and the link 31a has one end pivoted to the lever 26a at a point spaced inward from the extremity of the lever. Both the moveable cutter jaw 32a and the fixed cutter jaw 36a are here shown in somewhat modified form or shape, which, however, they need not necessarily be, but their functioning is the same as above described. The fixed cutter 36a is also shown lacking the projection 41, merely to indicate that the attachment in both forms could function without this projection although in the latter case there may always be present the danger of the difficulty above-mentioned regarding the fabric being fed in.

It is obvious from the linkage illustrated in Fig. 5 that as the needle holder 12 moves up and down the moveable cutter jaw 32a will move conversely, that is, down and up. With this simple and sole difference in manner of operation as an exception, the modified form of the attachment functions exactly as the form first described and accomplishes the same ends with the same efficiency.

It is apparent that the cost of either of the forms of the attachment shown and described, is insignificantly small compared with the cost of a special edge cutter machine such as those in common use today, which machine or machines, as mentioned above, are idle a substantial part of the working day in many shops. Moreover, experience with the attachment has demonstrated that the operation of simultaneously sewing and cutting the edge can be performed better and at a greater speed than is possible on the standard edge cutter machines to be found on the market. The complete separation and independence of the attachment from the machine proper and any part of the internal mechanism thereof, substantially simplifies the matter of repairs or replacement of parts.

Obviously, modifications in form and structure may be made without departing from the spirit or scope of the invention.

We claim:

1. In combination with a sewing machine having a head having a vertical foot bar and a vertically reciprocating needle bar depending from said head, an edge cutter attachment adapted to be mounted on the machine comprising a vertical plate having a cutter jaw fixed thereto and extending therefrom, said plate having a fabric guide foot rigid thereon and later-

ally spaced from said fixed jaw, in substantial parallel relationship therewith means for securing said foot to said foot bar, a second cutter jaw pivotally mounted on said plate, said needle bar having a pin thereon extending horizontally therefrom, and a linkage connecting said moveable jaw with said pin whereby reciprocal movement of said needle bar imparts a scissors-like action of said moveable jaw with respect to said fixed jaw.

2. The combination set forth in claim 1, said linkage including means for synchronizing said action of said moveable jaw with said movement of said needle bar so that both said moveable jaw and said needle bar rise and fall together.

3. The combination set forth in claim 1, said linkage including means for reversing said action of said moveable jaw with respect to said needle bar so that downward movement of said needle bar imparts upward movement to said moveable jaw and vice versa.

4. A cutter attachment for a sewing machine comprising a frame having a cutter jaw thereon, said frame having a guide foot fixed thereon and laterally spaced from said fixed jaw in substantially parallel relationship therewith, a moveable jaw pivotally mounted on said frame in scissors-like relationship to said frame jaw, said foot having means for securing the same to the vertical foot bar of the sewing machine, a lever pivoted to said frame, a link connecting said lever with said moveable jaw providing means for imparting up and down movement through an arc of said moveable jaw upon similar movement of one end of said lever, and means for attaching said end of said lever to the reciprocating needle bar of the machine for imparting said movement to said end of said lever.

5. An attachment for and adapted to be used in combination with a sewing machine having a vertical foot bar and a reciprocating needle bar depending from the head of the machine, comprising a substantially upright frame having a guide foot secured to one side of the forward edge thereof and having a fixed cutter jaw secured to the other side of said frame and extending forward thereof in spaced substantially parallel relationship with respect to said foot, means for securing said foot to said foot bar, a moveable cutter jaw pivotally mounted on said frame in scissors-like relationship with said fixed jaw, said needle bar having a horizontal pin secured thereto, and means connecting said moveable jaw with said pin for imparting scissors-like movement of said moveable jaw with respect to said fixed jaw upon reciprocating movement of said needle bar.

6. The device set forth in claim 5, said fixed jaw having a projection on the underside thereof extending to a level below the level of the underside of said fixed jaw.

7. The device set forth in claim 5, said means comprising a lever pivoted adjacent one end to said frame and having a longitudinal slot in the other end thereof, said pin registering in said slot, and a link joining said lever and said moveable jaw.

8. The device set forth in claim 1, said linkage comprising a lever pivoted adjacent one end to said frame and having a longitudinal slot in the other end thereof, said pin registering in said slot, and a link joining said lever and said moveable jaw.

9. In combination with a sewing machine having a vertical foot bar and a vertical recipro-

cating needle bar depending from the head thereof, an edge cutter including a guide foot secured to the foot bar and a scissors mounted substantially vertically and laterally spaced from said foot in substantially parallel relationship therewith, and means partly on said needle bar and partly on said scissors for imparting scissors cutting action to said scissors during reciprocation of said needle bar.

10. In combination with a sewing machine having a vertical foot bar and a reciprocating vertical needle bar depending from the head thereof, an edge cutter including a guide foot secured to the foot bar and a fixed cutter jaw mounted in spaced substantially parallel relationship therewith adjacent said foot, a moveable cutter jaw in scissors-like relationship with said fixed jaw, and means connecting said needle bar and said moveable jaw for imparting scissors-like action of said moveable jaw with respect to said fixed jaw upon reciprocation of said needle bar.

11. In combination with a sewing machine having a vertical foot bar and a reciprocating needle bar depending from the head thereof, an edge cutter comprising an upright frame having a guide foot on the forward end thereof, means for securing said foot to said foot bar, a fixed cutter jaw secured to said frame adjacent said foot in spaced substantially parallel relationship with respect to said foot, a lever pivotally mounted on said frame above said fixed jaw and having a cutter jaw thereon juxtaposed in scissors-like position with relation to said fixed jaw, said needle bar having a horizontal pin mounted thereon, and means connecting said pin with said lever for imparting reciprocating movement through an arc to said lever upon reciprocation of said needle bar thereby imparting scissors-like action of said last-named jaw with respect to said fixed jaw.

12. The combination set forth in claim 11, said means comprising a second lever having a slot in one end thereof, said pin registering in said slot, the other end of said second lever being pivoted to said frame, and a link joining said levers.

13. The combination set forth in claim 11, the pivotal mounting of said lever being positioned intermediate the length of the lever, said means comprising a second lever having a slot in one end thereof, said pin registering in said slot, the other end of said second lever being pivoted to said frame, and a link having one end pivoted to the end of said first lever and the other end pivoted to said second lever adjacent but spaced from said other end of said second lever.

14. The combination set forth in claim 11, the pivotal mounting of said lever being positioned intermediate the length of the lever, said means comprising a second lever having a slot in one end thereof, said pin registering in said slot, a link having one end pivoted to the end of said first lever and the other end thereof pivoted to the other end of said second lever, said second lever being pivoted to said frame at a point adjacent but spaced from said other end of said second lever.

15. The combination set forth in claim 11, said fixed jaw having a downward projection on the end thereof projecting below the lower level of said frame to prevent the fabric being fed into the machine from riding under said fixed jaw.

16. The combination set forth in claim 1, said

pin having releasable means securing the same to said needle bar whereby the vertical level of securement of said pin to the needle bar may be varied.

17. In combination with a sewing machine a head having a vertical foot bar and a vertically reciprocating needle bar depending from said head, an edge cutter attachment adapted to be mounted on the machine comprising a frame having a cutter jaw fixed thereto and extending therefrom, said fixed jaw having a downward projection thereon to prevent fabric being fed into the machine from riding under said fixed jaw, means for securing said frame to said foot bar, a second cutter jaw pivotally mounted on said frame, said needle bar having a pin thereon extending horizontally therefrom, and a linkage connecting said movable jaw with said pin whereby reciprocal movement of said needle bar imparts a scissors-like action to said movable jaw with respect to said fixed jaw.

18. A cutter attachment for a sewing machine comprising a frame having a cutter jaw thereon, a movable jaw pivotally mounted on said frame in scissors-like relationship to said frame jaw, said frame having means for securing the same to the vertical foot bar of the sewing machine, said frame being adapted to be positioned on said foot bar at a level such that when said foot bar is in its uppermost position said frame jaw leaves a clearance space between the lower edge thereof and the table of the machine, and means closing said clearance space at the forward

end of said frame jaw to prevent fabric being fed into the machine from riding under said frame jaw, and means connecting said movable jaw to the reciprocating needle bar of the machine whereby reciprocating movement of said needle bar imparts scissors-like movement to said movable jaw.

19. The device set forth in claim 18, said clearance closing means comprising a downward projection rigid with said frame jaw at the forward end thereof.

20. The combination set forth in claim 9, the lower jaw of said scissors having a downward projection at the forward end thereof adapted to prevent fabric being fed into the machine from riding under said lower jaw.

21. The combination set forth in claim 11, said pin having a clamp rigid with one end thereof, said clamp having said needle bar registering slidably between the jaws of the clamp, and releasable means for tightening said jaws about said needle bar thereby mounting said pin on said needle bar.
